UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT.

CASKET HANDLE.

Application filed February 28, 1921. Serial No. 448,295.

To all whom it may concern:

Be it known that I, EDWARD R. SARGENT, a citizen of the United States, residing in the city and county of New Haven, State of Connecticut, have invented certain new and useful Improvements in Casket Handles, of which the following is a full, clear, and exact description.

This invention relates to casket handles and more particularly to that type of casket handles wherein the handle bar is suspended from the plates which are attached to the body of the casket by a pair of supporting arms. The handle bar usually consists of a body portion or tube of sheet metal or suitable material to which is secured the ornamental tip which may be made of soft metal or the like.

The connection between the tip and the tube has usually been effected in the past by means of a wooden plug which is first driven into and secured in a projecting position in the open end of the tube, after which the tip is placed upon the end of the tube and then secured by means of a pin or the like to the projecting end of the plug. The fastening means just described has always been used in the case of the round handle bars and has sometimes been used in the case of bars of polygonal shape. The tips have sometimes been secured upon bars of the latter shape, however, by the provision of a pin or a small brad passing through the tip and through depressions formed in the sheet metal bar, as shown in my Patent No. 1,030,434, granted June 25, 1912. The present application aims then to provide a simplified means of connecting the handle bar to the ornamental tip which is provided on each end of the same.

One object of this invention is to provide a simple and economical method of securing the tip upon the handle bar of a casket handle, without the use of the wooden plug referred to above, although such plug may be employed, if desired, to give added strength to the bar.

Another object of the invention is to provide interengaging means upon the tip and the bar of the casket handle, so that the parts of one of these members may be locked directly to the parts of the remaining member without use of a third member to connect the two together. This obviates the use of a pin or separate fastening means for the two

members and provides a satisfactory and efficient means for securing them together. 55

A still further object of the invention is to provide the tip and bar of a casket handle with means which may, after the tip and bar are assembled, be turned or bent into interlocking position so as to prevent the separation of the two parts. 60

To these and other ends the invention consists in the novel features and combinations of parts to be hereinafter described 65 and claimed.

In the accompanying drawings:

Fig. 1 is a front elevational view of a casket handle embodying my improvements;

Fig. 2 is an enlarged detail view of the 70 under side of one end of the casket handle showing the means by which the tip is secured to the handle bar;

Fig. 3 is a view similar to Fig. 2 partly in section along the line 3—3 of Fig 2; 75

Fig. 4 is a modified form of my invention showing the same applied to a casket handle of polygonal cross-section;

Fig. 5 is a view similar to Figs. 2 and 4, but showing a modified form of means for 80 attaching the tip to the bar;

Fig. 6 is a view similar to Fig. 5 showing another modification of my invention;

Fig. 7 is a sectional view on line 7—7 of Fig. 5; 85

Fig. 8 is a sectional view on line 8—8 of Fig. 6;

Fig. 9 is a sectional view on line 9—9 of Fig. 5;

Fig. 10 is a view similar to Figs. 2, 4, 5 90 and 6, but showing a modified form of my invention as applied particularly to a sheet metal tip; and

Fig. 11 is a sectional view on line 11—11 of Fig. 10. 95

In Fig. 1 of the drawings, I have shown a casket handle in its entirety consisting of the socket plates 10, to which are pivotally connected the arms 11 which support the handle bar 12 in the usual manner. Provided upon each end of the handle bar 12 is the usual tip 13, which is commonly made of ornamental soft metal or the like. To obviate the use of the wooden bar or plug which is commonly inserted within the round bar, I have provided a means by which the sheet metal tube or bar 12 may be connected directly to the tip. The tips

13 usually are provided with a shoulder 14, as clearly shown in Fig. 3, the tip or bar 12 being adapted to be received within the end of the tip and lodged against the shoulder 14, so that relative movement between the tip and bar will be limited in one direction by contact of the tube against the shoulder. A projecting lug or lip 15 is struck up from the metal of the bar at the end thereof and is adapted when the tube and bar are assembled to be turned or bent up to engage the walls of an opening 16 provided upon the underside of the tip. This lug is usually provided by cutting two slits 17 from the edge of the tube 12, so that the portion of the sheet metal between these slits may be readily bent up about the side remaining uncut. As shown in Fig. 2, the width of this lug or the distance between the slits is preferably made approximately the same as the width of the opening or recess 16, so that when the lug is bent up into this opening, the tip will be secured against any rotary movement upon the arm as well as longitudinal movement relatively thereto.

In Fig. 4 I have shown a tube or bar 12' of substantially square cross-section, which is attached to the tip 13' as before described in connection with Figs. 2 and 3. The lug 15 is in this case bent up to engage the walls of the opening or recess 16 provided in the tip 13' in the manner previously described. It will be apparent that in the case of the bar of polygonal shape it will not be so essential to provide means for preventing relative rotation of the bar and tip for the shape of the bar and the socket within the tip which receives the bar will serve to prevent such movement.

In Fig. 5 I have shown a modified form of connection between the arm and bar, and while this is shown in connection with a bar of substantially square cross-section, it will be understood that it is not limited thereto, but may be applied to a bar of circular cross-section as well. The tube or bar 12' is provided with a lug 17, which is struck up longitudinally of the bar and is adapted to enter a slot 19 provided in the tip. This slot is L-shaped so as to provide one arm extending longitudinally of the tip and a second arm or recess 20 which communicates therewith extending transversely of the tip. The upstanding lug 17 is adapted to be cut or slit to provide a small portion

21 at one end thereof, which may be bent within the recess 20 when the parts are assembled together. It will be obvious that the parts will now be locked in position so that no relative movement will be permitted between them. The tip in this case may or may not be provided with the shoulder 14, as the small portion 21 of the lug 17 fits relatively tightly within the recess 20, movement of the bar within the tip in either

direction will be prohibited without the provision of the shoulder.

In Fig. 6 I have shown still another modified form of my invention wherein two opposed L-shaped slots 19 are provided in the tip, which slots include the recesses 20 for the reception of the lugs 22, which are struck-up from the sheet metal bar, so that they are received within the slots 19 when the tip and bar are assembled and which may then be bent laterally into the recesses 20 to lock the parts in position. It will be noted that the lugs 22 are in this modification approximately the same width as the recesses 20, so that the entire lug will be bent laterally within the recess instead of just a portion of the lug, as has been described in connection with the modification shown in Fig. 5.

In Fig. 10 I have shown still another modification of my invention, which is particularly adapted to be used in connection with a structure in which a sheet metal tip is connected to the usual bar. It will be understood, however, that this construction is not confined to the use of a sheet metal tip, but may be in some instances used in connection with a tip of soft metal. As shown in this figure, a recess 23 is provided in the bar 12', the tip 24 being provided with the lug 25 which may be bent vertically within the opening or recess 23 to lock the two parts together. This structure is in some aspects a reversal of the structure shown in Figs. 2 and 3, wherein the recess or opening is provided in the tip and the lug provided upon the tube or bar to be bent vertically into the opening of the tip to lock the parts together. While one of these arrangements may be found more suitable in connection with some types of casket handles and another may be found more suitable with others, it is to be understood that the claims of this application are to be construed broadly enough to cover all forms and it is not intended to limit the claims or the invention described herein to any one of the forms shown.

While I have shown and described the preferred forms of my invention, it will be understood that the same is not to be limited in all its aspects to the details shown, but is capable of other modifications and variations which will fall within the spirit of the invention and within the scope of the appended claims.

What I claim is:

1. In a casket handle, a handle bar, a tip telescopically mounted thereupon, one of said members being provided with a slot, and the other provided with a lug bendable into engagement with the slot after the tip is assembled upon the arm.
2. In a casket handle, a hollow handle bar, a tip adapted to telescopically receive the end of said bar, and a tongue cut from the

bar and adapted to be bent into engagement with a part of the tip after the parts have been assembled.

3. In a casket handle, a handle bar, a tip adapted to be slipped upon said bar, and means for securing said parts together including a projecting member upon one of the parts, the other part being provided with means to interlock with said member, said member being bendable to interlocking position only after the parts are adjusted to a final position relatively to each other.

4. In a casket handle, a handle bar, a tip adapted to telescopically receive said bar, a lug cut from one of said members and bendable outwardly after the parts have been assembled into engagement with the other member to hold said parts in position.

5. In a casket handle, a hollow handle bar, a tip therefor, a lug cut from one of said members and bendable vertically into engagement with the other member after the parts have been assembled to secure the tip upon the arm.

25 6. In a casket handle, a handle bar having a lug cut therefrom, a tip provided with an opening, said lug being bendable into said opening to engage the walls thereof to secure said parts together.

30 7. In a casket handle, a handle bar, a tip constructed to telescopically receive a portion of said bar and having an abutment to limit relative movement of the parts in one direction, and interengaging means on said members including a vertical lug and opening to prevent other movement thereof.

8. In a casket handle, a handle bar, a tip therefor adapted to be slipped upon the end of the bar, and a laterally projecting lug upon said bar adapted to be bent into engagement with the tip to secure said parts together.

9. In a casket handle, a handle bar, a tip provided with a slot, a projection upon said bar adapted to enter said slot when said tip and bar are assembled and to be bent into engagement with a portion thereof to prevent separation of the parts.

10. In a casket handle, a handle bar, a tip therefor, one of said members being provided with an angled slot, the other member having a projection entering one arm of said slot when the parts are assembled and arranged to be bent into the other arm thereof to lock said members together.

55 11. In a casket handle, a handle bar, a tip therefor provided with an angled slot and a projection struck up from the metal of the bar and adapted to enter longitudinally into one arm of said slot and to then be bent laterally into the other arm thereof to lock said parts together.

60 12. In a casket handle, a handle bar, and a tip therefor provided with a pair of opposing L-shaped slots, said parts being secured together by having integral portions bent upwardly from the handle bar to engage said slots.

In witness whereof, I have hereunto set my hand on the 25 day of February, 1921.

EDWARD R. SARGENT.
